Primary Examiner — Patricia A Palasik(74) *Attorney, Agent, or Firm* — Knobbe, Martens, Olson & Bear, LLP(57) **CLAIM**

The ornamental design for a robotic shuttle, as shown and described.

DESCRIPTION

FIG. 1 is a perspective view of the robotic shuttle;

FIG. 2 is a front view thereof;

FIG. 3 is a rear view thereof;

FIG. 4 is a left side view thereof; and,

FIG. 5 is a top view thereof.

1 Claim, 5 Drawing Sheets(56)
